UNITED STATES PATENT OFFICE.

WILLIAM MEISCHKE-SMITH, OF LONDON, ENGLAND.

MACHINE FOR DELIVERING MEASURED QUANTITIES OF LIQUIDS.

1,123,133.

Specification of Letters Patent. Patented Dec. 29, 1914.

Application filed November 22, 1911. Serial No. 661,647.

To all whom it may concern:

Be it known that I, WILLIAM MEISCHKE-SMITH, a subject of the King of Great Britain, residing in London, England, 5 (whose post-office address is The Asiatic Petroleum Company Limited, of 24 and 28 St. Mary Axe, in the city of London, England,) civil engineer, have invented a certain new and useful Improved Machine for 10 Delivering Measured Quantities of Liquids, of which the following is a specification.

The invention relates to machines for filling oil tins with a constant weight of oil, and applies more particularly to the arrangement by which a number of these cans or tins are placed on a square support on a turn-table, so that all the tins on one side are filled at the same time by nozzles connected to the separate compartments of a large container. It is important in practice that each tin should contain the same predetermined weight of oil irrespective of the changes of density of the liquid due to temperature or other causes. For this purpose the volume of the oil discharged from its compartment into the respective tins must vary according to the density, that is the effective capacity of each compartment must be adjusted correspondingly, and for practical efficiency this change of capacity should be effected simultaneously for all the compartments. Arrangements have been proposed for altering the capacity of the compartment according to the specific gravity of the different liquids used as shown by an index, and plans have also been proposed to alter the capacity according to the temperature, when the same liquid is always employed, but no arrangement has hitherto been known in which the capacity of the compartments can be adjusted for liquids of different specific gravities at varying temperatures by setting an index to the corresponding graduation on a fixed scale. According to the present invention, when the density of the oil has been determined by a preliminary operation, the requisite change of capacity of each compartment is simultaneously effected by setting a hand to the graduation of a dial corresponding to this density, and should any change of temperature occur affecting the density of the oil, the capacity change is effected by moving a second pointer connected to a spindle carrying both pointers to a graduation on the same dial

corresponding to the temperature as shown by a thermometer immersed in the liquid. The adjustment is rapidly made simultaneously for every compartment by simply observing the thermometer and turning a hand wheel until the pointer connected to the hand wheel shaft by suitable gearing is opposite the actual temperature at the time, as shown on the graduated dial. According to the invention also the rotation of the shaft connected to the hand wheel adjusts simultaneously the axial positions of the end plates of drums, one of which is fixed in every compartment, so as to vary the capacity of these compartments as required. 60 Also improved means are described of releasing the air during the process of filling the compartments with oil and of lowering the nozzles and opening the discharge stop cocks when the compartments are being 70 emptied.

Figure 1 is a part side elevation showing one compartment in section, Fig. 2 an end elevation of a machine constructed according to the invention, Fig. 3 is a complete 80 plan view to a reduced scale, Fig. 4 shows one of the air release valves, Fig. 5 is a sectional elevation, to enlarged scale, of one of the compartment drums with an adjustable end plate, Fig. 6 is a sectional plan of a 85 portion of the containing vessel, showing the compartment of Fig. 5, and Fig. 7 is an end elevation of a part of the compartment casing and containing vessel.

In the figures, 1 represents the separate compartments of the containing vessel, 2 the cylindrical drum, whose capacity can be varied by the axial displacement of the end plate 3, rigidly attached by the key 6 to the shaft 4, which can be turned by the hand wheel 5, not shown in Fig. 2. The end plate 3 has a screw thread on its outer circumference engaging with a screw thread on the inner circumference of the fixed cylinder 2. Small holes at the top of this fixed end allow the space between the fixed and movable ends of the cylinders to be filled with the oil. On the exterior of drum 2, a plurality of guide members 2' having slotways 2² running parallel with the axis of the drum are fixed Figs. 5-7. A bolt 7, having a threaded portion screwable in a boss 1' on the side of the compartment 1, is adapted to be turned so that its terminal point may enter or be withdrawn from the 105

slot of one or other of the guides when brought into register with it. When the point of bolt 7 engages a slot 2², the drum is held fast, but when the point is withdrawn, the drum is free to be rotated by hand through a hand hole provided with a cover 8. When it is required to adjust the capacity of any compartment independently of the others, the associated bolt 7 is released 10 and the cylinder 2 rotated by hand through the hand hole and again fixed by means of bolt 7. To the cover 8 a piece of hard wood is attached; by reducing, or if necessary entirely removing, this piece, the capacity of 15 the compartment may be considerably increased when required. By the means described the capacity of each compartment of the machine may in the ordinary construction be varied so as to deliver the same 20 weight of oil for any specific gravity between the limits of .78 and .85, but this range can be varied in the construction of the machine to suit special requirements. It is obvious that other equivalent 25 devices for displacing the movable end of the cylinder may be substituted for the screw threads shown by way of example.

The shaft 4 is connected by the reducing gear 9 to the spindle 12 which carries the 30 two pointers 10 and 11. Both pointers move over a dial 14 provided with two scales 14', 14², the one graduated in terms of density, the other in degrees of temperature. In adjusting the capacity of each compartment, 35 the density of the oil is determined in the ordinary way by drawing off a small quantity by a stop cock 38^b provided on the reservoir 38 for this purpose; the hand wheel 5 is then turned until the pointer 10 is opposite the graduation showing this density on the density scale 14' of the dial 14. The temperature of the oil is then read off from 40 a thermometer, preferably of the circular form with dial 38^a, immersed in the reservoir 45 at a position where it can be readily seen by an operator at the hand wheel 5. The hand 11 which is loose on the spindle is then turned until it is opposite the graduation corresponding to the actual temperature on 50 the scale 14² on the dial 14 and clamped in this position by the milled nut 13. The temperature scale is graduated so that the indications represent the changes of density 55 corresponding to the changes of temperature. Should the temperature vary at any time after the hands have been set as described, the operator has only to adjust the hand 11 to the temperature, as shown by the immersed thermometer by means of the 60 hand wheel 5 and the shaft 4 will also be turned with the spindle 12 so as to adjust the volume of the cylinder in each compartment as required to deliver the required 65 weight of oil into the tins when the compartments are emptied. The hand 10 points

always by this device to the density of the liquid under the existing conditions. The shaft 4 is supported in bearings, where it passes through the dividing walls of the compartments and at the end compartment 70 nearest to the hand wheel 5 is packed so as to be oil tight by means of the stuffing box and gland 15.

Oil is admitted to the compartments from a reservoir 38 through a main valve in 75 the valve casing 16, which is opened and closed by the spindle 17 turned by the hand wheel 18. An air vessel 39 is attached to the reservoir to absorb any shocks on opening or closing the main valve. When the 80 main valve is opened, oil flows into the central chamber and when this is filled flows into the adjacent chambers on either side through the semi-circular spaces 19 provided as shown at the top of the junction of two 85 adjacent compartments. Air escape valves 20 (Figs. 1 and 4) are provided at the top of the end compartments. The valves are weighted so as to remain open against the escaping air but so as to close under the 90 flow of oil which occurs when the compartments are all filled and the oil reaches the level of the valves. The weights tending to keep the valves open can be adjusted depending upon the head or pressure at which 95 the oil is admitted, so as to minimize the amount of oil escaping by the overflow pipe 40. When the weights on the valves are seen to rise, the main valve 16 is closed by the hand wheel 18. The lever 21 is then pulled 100 down to open by means of the common sliding bar 23 the air stop cocks 22 fitted to each compartment, which release any air confined in the spaces 19. The lever 21 in its lowest position lies in the path of the handle of the valve wheel 18 and prevents the wheel from being turned and the main valve 16 opened at the wrong time.

When the compartments have been filled 110 the hand wheel 24 is turned so as to move the sliding bar 25 to the right by means of the screwed rod 26, so as to lower the nozzles 27 into the tins placed below them. These nozzles are pulled down by weights 115 28 and the attached sleeves 29 slide over the pipes leading from the compartments. Projecting pins 32 on the sliding bar 25 press against the arms 31 of the two-armed levers. When the bar is moved to the left, the arm 30 of these levers is raised and by means of the rollers 33 lifts the bar 34, which raises the nozzles by the collars 35. When the sliding bar 25 is moved to the right, the weights attached to the nozzles cause the bar 34 to fall into the lower position, in 120 which the nozzles are placed in the tins. In this position the slotted links 35^a are moved by the pins 36 attached to the sliding bar 25 so as to open the stop cocks 37 on the discharge pipes of the compartments. 130

When the contents of the compartments have been emptied into the tins, the hand wheel 24 is turned in the opposite direction, the nozzles are raised, and the cocks shut.

- 5 In the construction of the machine shown, there are nine compartments, each compartment holding 33½ lbs. of oil, but the number and capacity of the compartments can obviously be varied as may be required
10 for any specific purpose.

Having now described the nature of this invention and the best means I know of carrying the same into practical effect, I claim:—

- 15 1. A machine for filling a plurality of receptacles simultaneously with a predetermined weight of oil or other liquid irrespective of the varying density thereof, comprising in combination, a liquid-containing vessel having a plurality of compartments, a shaft rotatably mounted within the vessel, means for rotating said shaft, and means correlated with the said shaft for varying simultaneously the effective capacity of each
20 compartment in accordance with changes occurring both in the density and in the temperature of the liquid to be weighed in the receptacles.

2. A machine for filling a plurality of receptacles simultaneously with a predetermined weight of oil or other liquid irrespective of the varying density thereof, comprising in combination, a liquid containing vessel having a plurality of compartments, an
30 adjustable device arranged in each compartment, each device comprising two interconnected space inclosing members, one member adjustably fixed within the corresponding compartment and the other member shift-
35 ably mounted therein, means for moving simultaneously in each device the shiftable member toward and away from the fixed member whereby the space inclosed by the members may be altered and the effective
40 capacity of each compartment simultaneously varied in accordance with changes occurring both in the density and in the temperature of the liquid to be filled into the receptacles, and means in each compartment
45 releasably holding the fixed member of the adjustable device therein and operable to permit the relative adjustment of the members of the device in the compartment independently of the other devices.

- 55 3. A machine for filling a plurality of receptacles simultaneously with a predetermined weight of oil or other liquid irrespective of the varying density thereof, comprising in combination, a liquid-containing vessel having a plurality of compartments, a shaft rotatably mounted within the vessel, means for rotating said shaft, and means correlated with the said shaft for varying simultaneously the effective capacity of each
60 compartment in accordance with changes oc-

curing both in the density and in the temperature of the liquid to be weighed in the receptacles, said capacity-varying means consisting of a drum in each compartment, each drum comprising two relatively movable members, one member being carried by said shaft and adapted to be displaced thereby relatively to the other member so as to vary the space inclosed between said members, a fixed dial having a set of graduations 70 representing terms of density and a set of divisions representing degrees of temperature, a spindle rotatably mounted on the machine, a pointer fixed to the spindle, a gearing operatively connecting the said 75 shaft and spindle whereby the pointer may be caused to register with any one of the graduations when the shaft is turned, an index hand loosely mounted on the spindle adapted to be manually moved into register 80 with any one of said divisions, and means for clamping the index hand to the spindle in register with the desired division.

4. A machine for filling a plurality of receptacles simultaneously with a predetermined weight of oil or other liquid irrespective of the varying density thereof, comprising in combination, a liquid-containing vessel having a plurality of compartments, a shaft rotatably mounted within the vessel, 90 an adjustable device in each compartment and correlated with the said shaft for varying the effective capacity of each compartment in accordance with changes occurring both in the density and in the temperature 95 of the liquid to be weighed in the receptacles, said capacity-varying devices consisting of a drum, each drum comprising a pair of relatively movable members, one member being slidably carried by said shaft and the other member adjustably fixed within the corresponding compartment, means for rotating said shaft to displace simultaneously the drum members thereon, each relatively to the other member of a pair, so as to vary 100 the space inclosed between the members of said pairs, a fixed dial having a set of graduations representing terms of density and a set of divisions representing degrees of temperature, a spindle rotatably mounted 105 on the machine, a pointer fixed to the spindle, a gearing operatively connecting the said shaft and spindle whereby the pointer may be caused to register with any one of the graduations when the shaft is turned, 110 an index hand loosely mounted on the spindle adapted to be manually moved into register with any one of said divisions, means for clamping the index hand to the spindle in register with the desired division 115 120 and means in each compartment releasably holding the fixed member of the capacity-varying device in the compartment and operable to permit the adjustment of the fixed member of said device separately from and 125 130

independently of the fixed members of the capacity-varying devices into the other compartments for the purpose described.

5. A machine for filling a plurality of receptacles simultaneously with a predetermined weight of oil or other liquid irrespective of the varying density thereof, comprising in combination, a liquid-containing vessel having a plurality of compartments, a shaft rotatably mounted within the vessel, means for rotating said shaft, means correlated with the said shaft for varying simultaneously the effective capacity of each compartment in accordance with changes occurring both in the density and in the temperature of the liquid to be weighed in the receptacles, and air release valves mounted on the vessel and adapted to close automatically under the pressure of the liquid in the vessel flowing into contact therewith.

6. A machine for filling a plurality of receptacles simultaneously with a predetermined weight of oil or other liquid irrespective of the varying density thereof, comprising in combination a liquid-containing vessel having a plurality of compartments, an adjustable device in each compartment for varying the effective capacity thereof in accordance with changes occurring both in the density and in the temperature of the liquid to be weighed in the receptacles, each of said devices comprising two inter-connected space-inclosing members, one member adjustably fixed within its compartment and the other member shiftably mounted therein, means for moving simultaneously in each device the shiftable member toward and away from the fixed member whereby the space inclosed by the members may be altered and the effective capacity of each compartment thereby simultaneously varied, means in each compartment releasably holding the fixed member of the adjustable device in the compartment and operable to permit the adjustment of the fixed members of said device separately from and independently of the fixed member of the adjustable devices in the other compartments, and air-release valves mounted on the vessel and adapted to close automatically under the pressure of the liquid in the vessel flowing in contact therewith.

7. A machine for filling a plurality of receptacles simultaneously with a predetermined weight of oil or other liquid irrespective of the varying density thereof, comprising in combination, a liquid-containing vessel having a plurality of compartments, a shaft rotatably mounted within the vessel, means for rotating said shaft, means correlated with the said shaft for varying simultaneously the effective capacity of each compartment in accordance with changes occurring both in the density and

in the temperature of the liquid to be weighed in the receptacles, air release valves mounted on the vessel and adapted to close automatically under the pressure of the liquid in the vessel flowing into contact therewith, an air release cock fitted to each compartment and means for controlling said cocks simultaneously.

8. A machine for filling a plurality of receptacles simultaneously with a predetermined weight of oil or other liquid irrespective of the varying density thereof, comprising in combination a liquid-containing vessel having a plurality of compartments, an adjustable device in each compartment for varying the effective capacity thereof in accordance with changes occurring both in the density and in the temperature of the liquid to be weighed in the receptacles, each of said devices comprising two inter-connected space-inclosing members, one member adjustably fixed within its compartment and the other member shiftably mounted therein, means for moving simultaneously in each device the shiftable member toward and away from the fixed member whereby the space inclosed by the members may be altered and the effective capacity of each compartment thereby simultaneously varied, means in each compartment releasably holding the fixed member of the adjustable device in the compartment and operable to permit the adjustment of the fixed members of said device separately from and independently of the fixed member of the adjustable devices in the other compartments, air-release valves mounted on the vessel and adapted to close automatically under the pressure of the liquid in the vessel flowing in contact therewith, an air-release cock fitted to each compartment, and means for controlling said cocks simultaneously.

9. A machine for filling a plurality of receptacles simultaneously with a predetermined weight of oil or other liquid irrespective of the varying density thereof, comprising in combination, a liquid-containing vessel having a plurality of compartments, a shaft rotatably mounted within the vessel, means for rotating said shaft, means correlated with the said shaft for varying simultaneously the effective capacity of each compartment in accordance with changes occurring both in the density and in the temperature of the liquid to be weighed in the receptacles, air release valves mounted on the vessel and adapted to close automatically under the pressure of the liquid in the vessel flowing into contact therewith, an air release cock fitted to each compartment, means for controlling said cocks simultaneously, a plurality of discharge nozzles, each provided with a discharge cock, and means for simultaneously adjusting the height of

all the nozzles relatively to the corresponding receptacles and controlling the respective cocks thereof.

10. A machine for filling a plurality of receptacles simultaneously with a predetermined weight of oil or other liquid irrespective of the varying density thereof, comprising in combination a liquid-containing vessel having a plurality of compartments, an adjustable device in each compartment for varying the effective capacity thereof in accordance with changes occurring both in the density and in the temperature of the liquid to be weighed in the receptacles, each of said devices comprising two inter-connected space-inclosing members, one member adjustably fixed within its compartment and the other member shiftably mounted therein, means for moving simultaneously in each device the shiftable member toward and away from the fixed member whereby the space inclosed by the members may be altered and the effective capacity of each compartment thereby simultaneously varied, means in each

compartment releasably holding the fixed member of the adjustable device in the compartment and operable to permit the adjustment of the fixed members of said device separately from and independently of the 30 fixed member of the adjustable device in the other compartments, air-release valves mounted on the vessel and adapted to close automatically under the pressure of the liquid in the vessel flowing in contact therewith, an air-release cock fitted to each compartment, means for controlling said cocks simultaneously, a plurality of discharge nozzles, each provided with a discharge 35 cock and means for simultaneously adjusting the height of all the nozzles relatively to the corresponding receptacles and controlling the respective cocks thereof.

In testimony whereof I have signed my name to this specification in the presence of 45 two subscribing witnesses.

WILLIAM MEISCHKE-SMITH.
